UNITED STATES PATENT OFFICE.

WILLIAM O. BLASE, OF WILKES-BARRÉ, PENNSYLVANIA.

DESIGN FOR A CLEANER AND SMOKE-DEFLECTOR.

SPECIFICATION forming part of Design No. 29,288, dated August 30, 1898.

Application filed July 26, 1898. Serial No. 686,948. Term of patent 14 years.

To all whom it may concern:

Be it known that I, WILLIAM O. BLASE, a citizen of the United States, residing at Wilkes-Barré, in the county of Luzerne and State of Pennsylvania, have invented and produced a new and original Design for a Cleaner and Smoke-Deflector for a Pipe; and I do hereby declare the following to be a full, clear, and exact description of the same, reference being had to the accompanying drawing, forming a part thereof.

The accompanying drawing is a perspective view of a pipe-cleaner and smoke-deflector embodying my design.

The leading feature of my design consists of a stem which is provided with a spiral groove and having a head which on its under side is provided with radial grooves.

In the accompanying drawing, A represents the stem of the cleaner, which is approximately round in cross-section and is provided with a spiral groove *a*. The stem is provided with a head B, which is provided on its under side with radial grooves *b*.

Having now described my invention, what I claim as new, and desire to secure by Letters Patent, is—

The design for a cleaner and smoke-deflector for a pipe, substantially as herein shown and described.

In testimony whereof I affix my signature in presence of two witnesses.

WILLIAM O. BLASE.
